DOOR LOCK

Rush S. Hartman, Ewing Township, Mercer County, N. J.

Application April 9, 1934, Serial No. 719,674

3 Claims. (Cl. 292—63)

The present invention relates to locks for use on doors of various classes such as those of trunks, cabinets, refrigerated compartments and doors of closed burden vehicles such as freight 5 cars, automobile vans, trucks, and the like, which require a strong and secure lock which will not open accidentally because of vibration or other causes.

On motor truck bodies my improved lock will 10 hold a door tightly closed against vibration and by constantly retaining a pressure or pull on the door will automatically take up wear. It will also engage and draw the door up tightly when a twist or irregularity has occurred which would 15 prevent an ordinary bolt from entering the keeper. It is also of especial value for use on refrigerated compartment doors where a lock is desired which possesses the ability to draw the door to and maintain it in tightly closed position to prevent infiltration of heat and to retain a pressure even though wear or looseness 20 has occurred, and where the ordinary type of lock is not effective thereafter.

Furthermore, in doors of this type rather heavy 25 gaskets are generally employed which are usually so arranged that they must be tightly compressed in fully closing the door, and it is important that they be maintained in a compressed state by the lock to form a properly sealed closure. My improved lock is eminently suited for 30 this purpose as it provides distinct mechanical advantages in the operation of finally seating and securely locking the door whereby such refrigerator door gaskets and the like are easily 35 and quickly compressed between the door and its frame and thereafter maintained in compressed condition until released by unlocking the door.

A principal object of the present invention 40 therefore is to provide an improved double action door lock comprising means operable to seat the door in the frame from a slightly ajar position and thereafter securely hold it seated and locked.

A further object of the invention is to provide 45 a door lock having a movable latch member retractable within the confines of the door when the latter is opened but adapted for projection into a keeper in the door jamb when the door is being closed and then rotatable about a pivot 50 so as to engage the keeper and draw the door to fully closed position, and thereafter positively maintain it therein until it is desired to again unlock and open the door.

Other objects, purposes and advantages of the 55 invention will hereinafter more fully appear or

will be understood from the following description of certain embodiments thereof in which reference will be had to the accompanying drawings.

In said drawings:

Figs. 1 to 5 inclusive show one embodiment of the invention installed in a typical refrigerator truck door or the like, Figs. 1 to 3 being longitudinal sections through the door lock, its component parts and adjacent portions of the door 10 and door frame, showing the said parts in different positions assumed thereby at different periods in the operation of the lock.

More specifically, Fig. 1 shows the lock latch member retracted into the door and the door 15 partially ajar;

Fig. 2, the latch member projected into the keeper with the door in substantially the same position as in Fig. 1, and

Fig. 3, the latch member in engagement with 20 the keeper and the door fully seated in its frame and locked.

Fig. 4 is a staggered section on the line 4—4 in Fig. 3, line 3—3 in Fig. 4 indicating the plane 25 of section in the preceding figures.

Fig. 5 is a fragmentary staggered section on the line 5—5 in Fig. 4.

Figs. 6 to 9 inclusive show another embodiment of my improved door lock but with the door and 30 frame omitted, Figs. 6, 7, 8 generally corresponding to Figs. 1—3 inclusive, and Fig. 9 being a rear elevation of the lock as shown in Fig. 7 with certain parts broken away into section.

Figs. 10—13 show still another embodiment of 35 the invention, and respectively similarly generally correspond to Figs. 6—9 inclusive save that Fig. 13 shows the lock parts in the position illustrated in Fig. 12.

Referring now more particularly to the drawings, the door D and frame F in Figs. 1—5 inclusive, form no part of the present invention and may be of any suitable type, those specifically illustrated being chosen for convenience in showing the manner of operation of this embodiment of the invention in association with a refrigerator truck door provided with a gasket G designed to be compressed against a substantially coextensive ledge L of the frame F when the door D is in locked position.

The lock itself, however, comprises a housing 45 I, providing a substantially rectangular elongated chamber having flanges 1a at its side edges desirably spot-welded to a base plate 2, and substantially enclosing the principal working parts, 50 55

screws 3, or other suitable means, being extended through the flanges and base plate to secure the lock to the door. The lock is operated by a longitudinally slideable rod 4 actuated from any convenient means (not shown) such as a mechanical linkage or by direct connection to an operating handle, mechanical linkage being usually desirably employed when several locks are provided in one door to secure it to the frame at several points, since all the locks may thereby be simultaneously actuated from a single mechanism. The rod 4 extends into the housing 1 through a suitable aperture in one end thereof and is preferably surrounded by a coil spring 5 bearing against the interior of the housing at one end and against the head 6 of the rod at the other. This head 6 may be integral with or formed separately from and secured to the end of the rod 4 in any suitable manner, and provides a slot 7 for reception of a latch member actuating pin 8, the ends of which projects outwardly from the head 6 through the side plates of the latch member hereinafter more particularly described and into guide slots 10 in the side walls of the housing. As is clearly apparent from Fig. 1, these slots extend substantially parallel to the rod 4 through a portion 10a of their length and are of arcuate form through another portion 10b whereby when the rod 4 moves longitudinally, the pin 8 is forced to travel along the slots without movement relatively to the head 6 during its passage through the parallel portion 10a and to move laterally through slot 7 simultaneously with its passage through the arcuate portion 10b. The latch member to which reference has been made may be formed as an integral unit, preferably of hardened steel or other suitable wear resistant material, and comprises a body 12 having a toe 13 adapted for projection into the keeper K in the door frame and a pair of side plates 14, 15 which lie in slideable engagement with the respective side walls of the housing 1 when the latch member is assembled therein, and are provided with circular apertures for the reception of the pin 8. Adjacent the inner end of the toe 13, the latch member is also provided with integral projecting bosses 16 which extend laterally outward in opposite directions through slots 17 in the side walls of the housing 1 and are slideable therein, these slots being parallel to the portions 10a of the slots 10.

The operation of the lock just described may conveniently be explained by reference to Figs. 1-3 inclusive, assuming that the door initially is unlocked and slightly ajar, with the latch member retracted into the housing as shown in Fig. 1. To lock the door when it is thus nearly but not quite seated in its frame, the rod 4 is moved longitudinally as shown in Fig. 2, thereby correspondingly sliding the pin 8 forwardly in the slots 10 and projecting the latch member outwardly from the door as the bosses 16 move forwardly through the slots 17. When the bosses 16 reach the outer ends of these slots their further movement is arrested and they then form a fulcrum or pivot about which the latch member swings upon further movement of the rod, the pin 8 sliding laterally in the slot 7 of the head 6 and the entire latch member rotating about the axis of the bosses 16 now at their outermost position in the slots 17. The toe 13 of the latch member is thus brought into engagement with the bearing face k of the keeper K and the door thereby forcibly drawn inwardly toward the

frame, compressing the gasket G against the ledge L and fully seating the door.

The spring 5 is usually made of sufficient compressive strength to retain the latch member in this position against ordinary vibration or pressure on the door or, if desired, may be made of sufficient strength to lock the door of its own force when the rod 4 is released from holding mechanism (not shown) provided for retaining it in retracted position against the action of the spring when the door is open. In either case, however, the spring offers considerable resistance to the unlocking of the door although, of course, it will be understood that, if desired, any means other than the spring for retaining the latch member in locked position may be employed or the spring may be positioned at any other convenient point suitable for producing the desired effect upon the lock mechanism.

As will be readily understood from the drawings, when the door is to be unlocked prior to opening, the rod 4 is retracted, thereby rotating the latch member about its pivots 16 in a counter-clockwise direction as viewed in Figs. 1-3 until restored to the position shown in Fig. 2, after which further retraction of the rod 4 draws the latch member into the housing and entirely releases the door. During the initial retraction or counter-clockwise movement of the latch member, the pin 8 travels along the curved surface 10b and the bosses 16 are thus held against the outer end of the slots 17 until the said movement is completed, this cooperation between pin 8 and surface 10b preventing the possibility, which might otherwise be present, of the latch member moving bodily in a right line upon the initial retraction of the rod 4.

It may be noted at this point that the function of the slot 7 is to allow sufficient lateral movement of pin 8 to enable rod 4 to reciprocate in a right line which is usually desirable, but under certain conditions where a slight angular movement of the rod is unobjectionable the connection between pin 8 and head or equivalent part 6 may be made directly and the slot omitted.

In the embodiment of the invention shown in Figs. 6-9 inclusive, substantially similar principles of operation are employed; no operating spring is indicated in these figures, however, since in this form of the invention it is usually more convenient to position the spring externally of the housing 1' in case a spring is to be utilized at all. The housing is here provided with a depending flap 1b extending parallel to the base plate 2' and forming therewith bearing surfaces 55 for the head 6' secured to the rod 4 whereby the head 6' is guided in its movement longitudinally of the housing. The head 6' preferably consists of a substantially rectangular bar having its forward end tapered and provided with a T-slot 60 7', the inner surfaces of which are rounded as clearly shown in Fig. 7.

The latch member 12' is provided with a rearwardly projecting web 20 having a transverse arcuate rib 21 extending laterally outward therefrom on either side of its rearmost edge and into the jaws of the T-slot 7' in the head 6', while adjacent the inner end of the toe 13' is formed a semi-cylindrical groove 22 adapted to engage a pivot pin 16' fixedly secured in the walls of the housing 1' adjacent its outer end and bridging the chamber in the housing. The base plate 2' is apertured adjacent its outer end to provide a slot 23 for a purpose which will hereafter appear.

This embodiment of the invention is substan-

tially similar in operation to that shown in Figs. 1-5, but utilizes a slightly different action to effect the rotation of the latch member about its pivot when the door is being finally seated. Thus, when the latch member 12' is moved from the position shown in Fig. 6 to that shown in Fig. 7 by longitudinal movement of the head 6', the groove 22 in the latch member is brought into engagement with the pivot pin 16' as the toe 13' of the latch member 12' is projected into the keeper K in the door frame. Further forward rightline movement of the latch member is now resisted by the pivot pin 16' and the latch member therefore rotates about the latter, the outer surfaces of the rib 21 sliding through the T-slot 7' in the head 6' and projecting the web 20 and rib 21 from the housing through the slot 23 provided for the purpose. During this rotation the toe 13' of the latch member engages the bearing face k of the keeper K, drawing the door firmly into seated position and locking it therein. As shown in Figs. 6-8, the left hand portion of the rib 21 is outwardly curved at 24 to provide a stop adapted to engage the head 6' in the slot 7' to prevent the latch member from being rotated too far if the door is open and thereby separating the latch member from connection with the head. By reverse movement of the head the door may be readily unlocked, the latch member initially rotating about its pivot 16' until restored to alignment with the housing, then moving longitudinally therein until the keeper is fully cleared and the latch member and associated parts are returned to the position shown in Fig. 6.

In the embodiment of the invention illustrated in Figs. 10-13 inclusive, a rack and pinion are utilized for actuating the latch member, and the head 6'' is therefore preferably provided with a slot 30 having teeth 31 forming a rack at its bottom, while the latch member 12'' is provided with complementary teeth 32 of suitable width to enter the slot, a portion 32a of which are arranged on an arc described about the center of the semi-cylindrical pivot receiving groove 22', while another portion 32b is arranged substantially in a right line. As clearly apparent from Figs. 10-12 inclusive, projection of the head 6'' downwardly in the housing 1'' moves the latch member 12'' outwardly therefrom until the groove 22' engages the pivot pin 16'' secured to the housing whereupon the latch member is rotated about this pin through the action of the teeth 32a, the toe 13'' thereby being brought into engagement with the bearing face k of the keeper K to fully seat the door, the teeth 32b being brought into mesh with the teeth 31 remote from the extremity of the head 6'' and further relative movement between the latch member and the head thereby prevented.

Retraction of the head through reverse movement of the rod 4 in releasing the lock rotates the latch member in the opposite direction about the pivot 16'' until restored to the position shown in Fig. 11, and then retracts it into the housing to permit the door to be opened.

It will be apparent that my improved lock is adapted for use in many types of doors and other closures particularly where it is necessary or desirable that mechanical means be provided for fully seating the door in its frame, as in doors for refrigerator compartments or the like provided with resilient gaskets designed to be maintained under compression by the doors when closed. Thus, when the lock is employed in a door of such character, the action of the latch

member in conjunction with the keeper first draws the door toward the frame until fully seated therein, compressing the gasket, and thereafter holds it firmly seated until released.

When a spring is used for effecting the movement of the latch member, the actuating handle or other corresponding mechanism is generally provided with means for holding the rod 4, and hence the latch member, in retracted position against the pressure of the spring when the door 10 is open, but such holding means are usually unnecessary when the spring is omitted and manually operated mechanisms solely utilized for positively moving the latch member.

Moreover, the several parts of my improved 15 lock may readily be made by stamping, die casting, drop forging and like operations so that the amount of machine work required is minimized, thus enabling the lock to be manufactured in commercial production relatively economically, 20 while if the base plate be permanently secured to the housing by spot welding or otherwise at the factory after the parts are assembled, the lock then forms a unit which may be readily mounted 25 in the door by the user.

While I have herein described certain embodiments of my invention with considerable particularity, it will be understood that I do not thereby desire or intend to limit or confine myself 30 in any way thereto as modifications thereof will readily occur to those skilled in the art as well as changes in the form and arrangement of the several parts, and may be made if desired without departing from the spirit and scope of the invention as defined in the appended claims. 35

Having thus described my invention, I claim and desire to protect by Letters Patent of the United States:

1. A door lock of the character described comprising a housing, a latch member slideable therein having a portion adapted for projection therefrom, means operable to slide the latch member longitudinally of the housing comprising a rod having a slotted head and a pin loosely carried in said head, extending transversely through 45 the latch member and having its ends respectively projecting into slots in the side walls of the housing, and a pair of bosses carried by the latch member and respectively projecting therefrom into other, substantially rectilinear, slots in said 50 side walls, each of said first mentioned slots having a rectilinear edge and an arcuate edge adjacent thereto respectively adapted for cooperation with the pin to effect successive rectilinear and pivotal movements of the latch member relatively to the housing. 55

2. A door lock of the character described comprising a housing having opposed pairs of slots in its side walls, one pair of said slots extending longitudinally of the housing and the other pair 60 having a portion similarly extending and another portion extending in a curve, a latch member slideable in the housing having a toe adapted for projection therefrom, bosses carried by the latch member respectively projecting into the first pair 65 of slots, means for moving the latch member relatively to the housing comprising a rod having a head provided with a slot, a pin extending through said slot and the latch member and having its ends projecting into the second mentioned pair of slots whereby initial movement of the rod when the latch member is fully retracted in the housing is operative to slide the latch member longitudinally therein until the toe has passed 70 out of the housing and said bosses engage the 75

ends of the first pair of slots, subsequent movement of the rod then serving to swing the latch member about said bosses as an axis to thereby bring the latch member to final locking position.

- 5 3. A door lock of the character described comprising a housing, a latch member slidably therein having a toe adapted for projection therefrom, means operable to slide the latch member longi-

tudinally of the housing, means carried by the housing forming a fixed pivot for the latch member, and means cooperable with said sliding means to effect pivotal movement of the latch member about said pivot in the plane of its path of sliding movement after said toe has been projected from the housing by such sliding movement. 5
